Primary Examiner — Susan Bennett Hattan*Assistant Examiner* — Marie Fast Horse(74) *Attorney, Agent, or Firm* — Harness, Dickey & Pierce, P.L.C.(57) **CLAIM**

The ornamental design for a one-piece fan housing, as shown.

DESCRIPTION

FIG. 1 is a top perspective view of a one-piece fan housing; FIG. 2 is a bottom perspective view of the one-piece fan housing of FIG. 1;

FIG. 3 is a bottom view of the one-piece fan housing of FIG. 1;

FIG. 4 is a top view of the one-piece fan housing of FIG. 1; FIG. 5 is a side view of the one-piece fan housing of FIG. 1; FIG. 6 is a side view from the opposite side compared to FIG. 5;

FIG. 7 is a front side view of the one-piece fan housing of FIG. 1; and

FIG. 8 is a rear side view of the one-piece fan housing of FIG. 1.
